UNITED STATES PATENT OFFICE

152,393

DESIGN FOR A DECANTER OR SIMILAR
ARTICLE

John D. Buckingham, Chicago, Ill., assignor to
Lucien Lelong, Inc., Chicago, Ill., a corporation
of Illinois

Application December 4, 1947, Serial No. 142,951

Term of patent 14 years

(Cl. D58—6)

To all whom it may concern:

Be it known that I, John D. Buckingham, a citizen of the United States, residing at Chicago, in the county of Cook, and State of Illinois, have invented a new, original, and ornamental Design for a Decanter or Similar Article, of which the following is a specification, reference being had to the accompanying drawing, forming a part thereof.

Figure 1 is a top plan view of a decanter or similar article, embodying my new design;

Figure 2 is a side elevational view of the decanter or similar article shown in Figure 1;

Figure 3 is a perspective view showing the side and top from a downward angle; and

Figure 4 is a perspective view showing the side and bottom from an upward angle.

I claim:

The ornamental design for a decanter or similar article, as shown.

JOHN D. BUCKINGHAM.
